Primary Examiner — Sandra Snapp*Assistant Examiner* — Katherine Glennon(74) *Attorney, Agent, or Firm* — Banner & Witcoff, Ltd.(57) **CLAIM**

The ornamental design for a shoe upper, as shown and described.

DESCRIPTION

FIG. 1 is a front perspective view of a shoe upper showing our new design;

FIG. 2 is a side view thereof;

FIG. 3 is a front view thereof; and,

FIG. 4 is an enlarged view of FIG. 3 with additional environmental features removed for clarity purposes.

The broken lines immediately adjacent to the shaded area define the bounds of the claimed design and form no part thereof. The unshaded regions within or adjacent to the shaded area form no part of the claimed design. The broken lines showing the remainder of the shoe are for environmental purposes only and form no part of the claimed design.
